UNITED STATES PATENT OFFICE.

LEE M. VANCE, OF DAVIS, CALIFORNIA, ASSIGNOR, BY DIRECT AND MESNE ASSIGNMENTS, TO THE VANCE COMPANY, INCORPORATED, OF DAVIS, CALIFORNIA, A CORPORATION OF CALIFORNIA.

STAPLE-RETAINER.

1,110,975.

Specification of Letters Patent. Patented Sept. 15, 1914.

Application filed October 10, 1912. Serial No. 725,094.

To all whom it may concern:

Be it known that I, LEE M. VANCE, citizen of the United States, residing at Davis, in the county of Yolo and State of California, 5 have invented certain new and useful Improvements in Staple-Retainers, of which the following is a specification.

This invention relates to an improvement in staple retaining devices for fence posts.

10 The primary object of the invention is to provide means which will be supported by the fence post for receiving the staples which secure the fence to the post, flaring their terminals and maintaining the same locked 15 against displacement.

A further object of the invention is to provide a staple retainer for concrete fence posts which may be placed in the post when it is molded and which will be supported on 20 the post without the use of securing devices.

In the drawings: Figure 1 is a perspective view of a post equipped with the staple retaining means; Fig. 2 is a view showing a portion of the post broken away to illustrate the manner in which the staple retainer is supported within the post; Fig. 3 is a side elevation of the retainer; Fig. 4 is a section on the line 4—4 of Fig. 3; Fig. 5 is a detail view showing a portion of the retainer and 30 the manner in which the staple is inserted.

The invention broadly contemplates the provision of a staple retainer which is placed in the post as the same is molded, and while the invention is intended for use in connection with concrete posts, it will be noted that 35 metallic posts may be slotted to receive the staple retaining means and that the construction is applicable wherever it is desired to maintain a staple against displacement.

40 The device comprises a plurality of plates 11 and 12. These plates have formed in one face obliquely disposed straight channels 13, the plates being preferably formed of sheet metal stamped to produce the channels, it 45 being noted that other material may be used in the construction of said plates. The channels 13 are placed at intervals throughout the length of the plates and in the assembled position thereof with their channeled 50 faces confronting, said channels are designed to coincide to form medially disposed grooves, rivets 14 passing through the plates between the grooves. These grooves extend entirely across the plates and are reversely

disposed at equal angles, alternate grooves 55 being parallel, the converging extremities 15 of said grooves being equally spaced on both adjacent edges of the plates, the distance between the converging extremities of the grooves being approximately of the same 60 length as the intermediate portion 16 of the staples.

It will be noted that while the plates are intended to be used as shown in Fig. 3, that is, with the rivets between the grooves which 65 receive the penetrating portions of one staple, the plates may be reversed, and thus if the edge portion 17 is disposed outwardly with respect to the fence post 18, the retaining means will operate as effectually as if 70 the edge 19 were disposed outwardly. The plates extend throughout the length of the post, the grooves being spaced to agree with the spacing of the longitudinal fence wires 20. The staple is inserted with its intermediate portion 16 embracing the fence wire, 75 its terminals 21 being placed within the grooves and the staple hammered into place. As the staple is forced between the plates, its penetrating portions will diverge, locking 80 the staple against displacement and securely clamping the longitudinal strands 20. It has been found in practice that when the staples are thus placed within the retainer, it is impossible to withdraw them without 85 severing the intermediate portion 16. Thus an effectual staple retainer is provided without the use of attaching means for securing 90 the retainer to the post. It will also be seen that the retainer may be easily and economically manufactured and that the various parts may be readily assembled and positioned within the post at the time the post is molded. When the plates are placed 95 within the concrete the grooves in the post are filled with clay or other material which will not harden to prevent the insertion of the staple.

Having described the invention, what is claimed is:

1. A staple retainer including plates, each plate having diagonally disposed and oppositely arranged straight channels pressed into one face thereof, said channels having their converging extremities longitudinally 105 spaced upon the plates and being adapted to coincide in the assembled position thereof with their channel faces confronting, said

coinciding channels forming medially disposed grooves adapted to receive the extremities of a staple, and means for securing the plates together.

5. 2. A staple retainer including plates having channels formed therein, said channels coinciding in the assembled position of the plates to form medially disposed grooves, said grooves being oppositely arranged in 10 angular relation upon the plates, alternate grooves being parallel, the converging extremities of said grooves being longitudinally spaced upon the plates and adapted to

receive the extremities of a staple, and means for securing the plates together.

3. A reversible staple retainer including plates secured together and having oppositely arranged angularly disposed grooves formed medially thereof, alternate grooves being parallel.

In testimony whereof I affix my signature in presence of two witnesses.

LEE M. VANCE. [L. S.]
